UNITED STATES PATENT OFFICE.

HERBERT S. THAYER, OF PROVIDENCE, RHODE ISLAND.

BUTTON.

SPECIFICATION forming part of Letters Patent No. 392,377, dated November 6, 1888.

Application filed April 18, 1888. Serial No. 271,058. (No model.)

To all whom it may concern:

Be it known that I, HERBERT S. THAYER, a citizen of the United States, residing at Providence, in the county of Providence and State 5 of Rhode Island, have invented certain new and useful Improvements in Buttons; and I do declare the following to be a full, clear, and exact description of the invention, such as will enable others skilled in the art to which 10 it appertains to make and use the same, reference being had to the accompanying drawings, and to the letters and figures of reference marked thereon, which form a part of this specification.

15 My present invention relates to an improvement in buttons, and has for its object to produce certain results which have not been hitherto obtained by any of the known methods.

20 This invention consists, primarily, of a button made from a blank, of leather, leather-board, or other suitable substance, said blank having its circumferential edges rounded and hardened, and its central portion softer than 25 said edges, or in the normal condition as it existed in the material from which it was cut, and adapted to receive the shank-eye or fastening device preparatory to being compressed to form the button, all as will be more 30 fully described hereinafter.

Figure 1 represents a plan view of a blank as cut from a sheet or strip of material. Fig. 2 is a sectional side elevation of the same. Fig. 3 is a plan view of the blank, with the 35 edges rounded and hardened. Fig. 4 is a central sectional side elevation of the same. Fig. 5 is a like view of the blank with an eye-shank inserted therein. Fig. 6 represents a complete button. Fig. 7 is a central sectional 40 view of the blank with a nail inserted. Fig. 8 represents a completed upholstery nail or button.

In carrying out my improvement the blank *a* is first cut from a sheet or strip of suitable 45 material, leather-board or leather being preferred, as illustrated in Figs. 1 and 2 of the drawings. The blank is then subjected to a rolling process, which compacts and hardens the corners and edge, forming the round- 50 edged blank *a'*, as illustrated in Figs. 3 and 4, leaving the central portion of the blank substantially in its normal condition as it existed

in the blank—that is, the edges and corners *c* of the blank are hardened, making them smooth and compact—while the fiber of the 55 central portion of the button-blank, where the eye-shank *b* or fastening device is to be inserted, is practically unchanged. The fastening device *b* is then inserted into the blank in any known manner, as illustrated in Figs. 60 5 and 7, the former having an eye-shank, the latter a nail-fastening secured therein. The blank, with the fastening inserted, is then subjected to a heavy pressure, which forms the blank into the desired shape, and firmly 65 secures the fastening device *b* therein, forming the complete button, as illustrated in Figs. 6 and 8 of the drawings. The buttons are then colored or finished to suit the requirements of the trade. 70

I am thus enabled to produce a button which is stronger and more durable than those at present in the market. The edges being hard and compact are not liable to flake or become rough and ragged. They are also 75 smooth, and therefore cannot injure the button-hole or other article in contact.

I do not claim in this specification the method of making buttons and analogous articles, as herein described, as the same is more 80 fully described and claimed in an application filed by me December 13, 1887, Serial No. 257,755.

Having described my invention, I claim—
1. The button-blank herein described, having hardened chamfered edges, and a central portion softer than said edges, or in the normal condition as it existed in the strip from which it was cut, and adapted to receive an eye-shank, nail, or other fastening device 85 preparatory to being pressed into shape to form a button, substantially as described.

2. As an improved article of manufacture, a button having rolled and hardened circumferential edges and provided with an eye-shank or other suitable fastening device, substantially as herein set forth. 95

In testimony whereof I affix my signature in the presence of two witnesses.

HERBERT S. THAYER.
